UNITED STATES PATENT OFFICE.

ADOLPHE PROSPER EGGIS, OF FRIBOURG, SWITZERLAND.

TYPE-WRITING MACHINE.

SPECIFICATION forming part of Letters Patent No. 380,792, dated April 10, 1888.

Application filed June 1, 1886. Serial No. 203,880. (No model.) Patented in England May 24, 1886, No. 6,935; in France August 5, 1886, No. 177,787; in Germany August 13, 1886, No. 39,044, and in Austria-Hungary November 7, 1886, No. 47,566 and No. 11,812.

To all whom it may concern:

Be it known that I, ADOLPHE PROSPER EGGIS, of Fribourg, in Switzerland, have invented a new and useful Improvement in 5 Type-Writing Machines, of which the following is a specification.

Letters Patent for this invention have been duly granted to me, as follows: In Great Britain, No. 6,935, dated May 24, 1886; in Austria-Hungary, No. 47,566 and No. 11,812, dated November 7, 1886; in France, No. 177,787, dated August 5, 1886, and in Germany, No. 39,044, dated August 13, 1886.

My new type-writer combines both the capital letters, the small letters, the figures, signs, and the punctuations, &c., and is capable of printing all of these, and it is of great simplicity and moderate cost.

In the accompanying drawings, Figure 1 is 20 a plan view of my type-writer. Fig. 2 is a front elevation of the same. Fig. 3 is a sectional elevation at the line *xy*. In this figure the mechanism is shown at the moment in which it is printing one letter. Fig. 4 is a side 25 elevation with a section through *yz*. Fig. 5 shows an inverted plan of the movable printer taken out of the apparatus.

In all the figures similar letters refer to similar pieces.

30 On a plate, A, are affixed two guides, B B, between which the beveled sliding foot-plate D is moved. The paper, F, is placed around the cylinder E, which is secured upon the foot-plate D, as it is shown by Fig. 4, and the paper is held in place by means of a fixed rod, G, and a movable rod, G'. The cylinder E is turned by means of a button, E'. A ratchet or toothed wheel, e, and pawl e' regulate the amount which the button E' can be turned and 35 determine hereby the space between two lines.

A toothed rack, H, affixed to the foot-plate D, is intended to cause the paper to advance one or more teeth at a time for each letter printed. One guide-plate B bears a support, 40 K, with a lever, k, pivoted thereto, and a pawl, k', engaging the tooth-rack H. On another support or post, L, affixed upon the plate A, bears a lever, l, whose office is to put the pawl k' out of gear by pressing the outer end

of l downward with the finger, when the foot-plate D is to be moved backward in its slide-way.

Upon the corners of the plate A are affixed three pillars, a' a' a', which bear a plate, A'. There is a large circular opening in the plate A', closed by means of the disk I when the apparatus is at rest. Said disk or circular-shaped plate I is affixed by means of a central bolt, i, to a frame, J, hinged to the back edge of the plate A' by means of hinges j. Plate I 60 can be revolved around the bolt i. A spring, j', also affixed underneath the plate A', presses the frame J, as well as plate I, upward, so as to maintain the same in the plane of the plate A', as shown by Fig. 2. The plate or disk I bears 65 on its upper face two bracketed arms, C' and S', of a peculiar shape and provided with knobs C and S. The lower face of I is provided with a circular range of types, one half of which is composed of capital letters and figures, the other half of small letters and punctuation-marks, as shown in Fig. 5.

Two springs, M M, affixed to the frame J, are provided with inking-rollers m m, which are pressed against the types of plate I to ink 75 the same.

There is a stud, N, (see Fig. 2,) secured upon the under side of the frame J, and the office of said stud is to press down the lever k as the disk I and frame J are depressed in the act of 80 printing, said movement causing the track H and foot-plate D to advance one tooth, thus feeding along the cylinder E and paper, F. The plate A' is, moreover, provided with a circular range of openings, O, disposed and 85 formed so as to give passage to the pointed end of one of the arms C' or S' when the latter is pressed downward. Each of those openings is marked with a letter or a figure. The position of the arm C' upon the plate I is determined in such a manner so that the companion letter or figure of any selected capital letter or figure on the plate A, and which stands for the opening in which said pointed end is 90 pressed down, shall simultaneously with such 95 selection come in place and with the depression of the plate I be printed upon the paper, F. The position of hook S' upon the plate I

is determined in like manner, so that the small letters and punctuations can in like manner be printed upon the paper, F.

The annular-shaped opening Q in the plate 5 A' permits of the passage of the pointed end of the arm S' when the pointed end of the arm C' is pressed into one of the openings O in the act of printing, or the pointed end of arm C' when S' is pressed into one of said openings.

10 An opening, R, placed at the periphery of the plate I, provides for supplying the inking-rollers m m with color when they become dry.

The working of my type-writer is as follows: If you wish to print, for instance, the capital letter A or the figure 5, you take in your hand 15 the knob C and turn the plate I until the pointed end of arm C' is placed over the opening of letter A or figure 5, and you press the knob down, and at the same time depress the 20 plate I and impress the type A or figure 5 upon the paper. If you have to complete a word—for instance, "April"—you take hold of the knob S and turn the plate I in the direction of the arrow until the arm S' is placed 25 over the opening marked P and press the knob downward. The stud N operates upon lever k and pawl k', depressing them and moving the rack H, plate D, and cylinder E, and causing the paper, F, to advance the necessary amount, 30 and just as the feed is completed and the paper stopped, the type p is pressed downward and impressed upon the paper the right distance from A, and these movements are repeated for each letter printed. The lever k is 35 returned to its normal position by a suitable spring, or by a counter-weight, as shown by dotted lines in Fig. 2. When the end of each line of printing is finished, the button E is turned, revolving the cylinder and advancing

the paper, F, a distance equal to one or more 40 teeth of the rack e. The lever l is pressed downward at its outer end, thereby raising its inner end, which lifts the pawl k' out of the teeth of the rack H, and frees the rack, so that the sliding foot-plate D, the cylinder E, 45 and paper, F, can be pushed backward to the starting-point, so as to begin another line.

I claim as my invention—

1. The plate A', having a central opening therein, letters, figures, and marks arranged 50 in an arc around one side of said opening, and perforations in said plate opposite each of them, in combination with a pivoted frame, J, hinged to said plate upon one edge, a disk, I, pivotally supported upon said frame and having type upon its under surface in opposite sets near the periphery, inking-rollers upon arms secured to the frame J, arms and knobs C S, pointers C' S', and a cylinder for the paper, and mechanism, substantially as specified, for operating the same, substantially as set forth.

2. The plates A and A' and connecting posts, forming the frame of the machine, the plate A' having a circular opening therein, in combination with the revolving type-disk I, the pivoted frame J, carrying said type-disk, the stud N upon the frame J, the post or support K upon the plate A, the lever k and pawl k', connected to said support K, the rack H, 65 70 sliding foot-plate D, and the post L and lever l, for releasing the rack and raising the pawl, substantially as specified.

ADOLPHE PROSPER EGGIS. [L. S.]
